WATERPROOF BUILDING MATERIAL

Allan Cheney, Melrose, Mass., assignor to The Cheney Company, a corporation of Massachusetts

Application November 22, 1934, Serial No. 754,343

4 Claims. (Cl. 72—127)

The present invention relates to a waterproof building material and aims generally to improve existing materials of that type.

One of the aims and objects of the invention is to provide an improved waterproof building material adapted for general usage when waterproofing is required. More particularly an object of the invention is to provide a waterproof building material that may be embedded within masonry walls providing a highly flexible material of substantial body adapted to provide a cushion or pressure-relieving joint and coated with metal to provide a protective coating for the body from water of infiltration so that the body will not disintegrate.

In the waterproofing of masonry buildings, it is desirable to insert in the masonry construction a waterproof course at each and every joint where moisture may penetrate the walls. At many places, as for example, around beams, spandrels, lintels, the joints are of the so-called expansion type, that is, there is a juncture of masonry of different structure or length which are subject to different expansions and contractions. In such cases it is desirable to provide a cushion or pressure-relieving joint to permit of relative expansion and contraction of the masonry elements without breaking or disturbing the mortar bond, and it is often necessary to bend the waterproofing material to conform to the joint. It is, therefore, highly necessary that the waterproofing material be highly flexible so that it may be readily bent to shape as well as compressible to a certain degree. The joints to be waterproofed are of varying lengths, some being relatively short lengths as compared with the length or width of the building, as for example, joints for lintels and sills and others, such as the joints between a floor and the brick or stone exterior facing which are substantially the length of the building. Hence, in providing a waterproofing material for such joints it is advantageous to provide a material that is readily bendable by hand without requiring special bending tools or machinery. Thus one of the aims and objects of the invention is to provide a material that may readily be bent by hand around an irregular joint, and which may be so angularly bent as to conform to irregular joints of the masonry.

Heretofore, it has been proposed to use a building paper felt or saturated fabric for this purpose but this method of waterproofing is not entirely satisfactory because paper felt and fabric tend to become disintegrated when imbedded in a masonry wall. Even a bitumen saturated paper

felt or fabric will, when subjected to moisture, disintegrate except when exposed to the air where it may readily be dried by evaporation.

According to the present invention, I provide a waterproof building or flashing material having a bitumen saturated fabric body of substantial thickness so as to function on a cushion or compressible body providing a pressure-relieving joint coated with a thin metal surface or sheet (such as copper) intimately secured to the fabric body, either on one or both sides, which metal surface or sheet is sufficiently thin as not materially to impair the flexibility of the fabric body, the material preferably being so constructed as to be bonded to a layer of mortar, so that upon hardening of the mortar, the masonry above or exterior the material will be restrained from shifting laterally.

Other principal as well as secondary objects and advantages of the invention will appear to those skilled in the art from a consideration of the following description and the accompanying drawing, wherein I have illustrated certain forms and constructions within the scope of the invention.

In the drawing:

Fig. 1 is a perspective view of one embodiment of the invention;

Fig. 2 is a fragmental sectional view taken on the line 2—2 of Fig. 3;

Fig. 3 is a similar view of a modified form of construction;

Fig. 4 is a fragmental plan view of a sheet of waterproof building material according to one form of the invention;

Fig. 5 is a similar view of a modified form of the invention;

Fig. 6 is a detail sectional view according to another form of the invention; and

Fig. 7 is a similar view of a further embodiment of the invention;

Fig. 8 is a similar view of another embodiment of the invention; and Fig. 9 is a detail sectional view of a portion of a masonry building illustrating one use of the invention.

Referring to the drawing, the invention comprises a flexible fabric body 10 of any suitable material such as building paper, felt, sheeting or drilling, preferably the latter. In the illustrated embodiment a sheet of heavy cotton drilling 11 may be thoroughly saturated and coated with bitumen, as for example, layers 12 of asphalt, to give it body, render it tacky, and water-repellent. This material may have a substantial body and being flexible and to a degree com-

pressible, is suitable for use as a pressure-relieving joint, and advantageously the fabric body may be about $\frac{1}{8}$ of an inch thick, and highly flexible so as to be readily bendable over a shouldered course of masonry, as for example, as shown in Fig. 9.

A very thin, flexible metal sheet 13, as for example, a 3-oz. copper sheet, is secured to at least one side of the fabric body, to provide a metal coating for the fabric body 10, and advantageously the metal sheet 13 may be adhesively secured to the fabric body 10 by rolling it under pressure between rolls, or otherwise, while spreading a coating of hot asphaltum between the sheet 11 and fabric body 10. When made in such manner, the metal sheet 13 is tenaciously bonded to the fabric 10. In some cases, it will be sufficient to provide a metal sheet 13 only on one side of the fabric body as is illustrated, for example, in Figs. 1 and 2, in which case I preferably press or roll into the opposite face of the body 10 ground or crushed mineral such as stone or slate 14 or other like material which may be imbedded in a layer of asphaltum 12. Or, if preferred, both sides of the fabric may be coated with a metal sheet 13 as in Fig. 3.

The metal coated surface of the material is preferably the upper surface, when the material is used as a waterproof cut-off in masonry walls, so as to provide a non-absorptive metal surface for draining any water of infiltration from the wall. The fabric body is thus shielded from water of infiltration but should the wall become damp, as by sweating, the metal sheet 13 in conjunction with the highly compressed stone surface 14 of the fabric body will retard absorption of moisture by the fabric body 10 and thus will prevent rapid disintegration of the body material, even though embedded within a masonry wall.

In using the material as a waterproof cut-off or flashing, it is often desirable to lay the waterproofing in a bed of mortar. When this is done with the form of material shown in Figs. 1 and 2 I find that the crushed stone surface 14 of the fabric body 10 makes an excellent bond with the mortar so that upon hardening of the mortar the material is held securely in place. Mortar, however, does not readily adhere to a smooth metal surface such as a copper sheet and hence to resist any tendency of the masonry adjacent the metal coated surface to shift laterally, I preferably provide raised projections or depressions around or in which the mortar may be molded. These projections may be in the form of raised conical shaped projections 17 (Figs. 1 and 4) or they may be in the form of ribs or grooves 18 (Fig. 5). In either form they may be readily pressed into the material.

Preferably the projections 17 and 18 are arranged in rows (see Figs. 4 and 5) lengthwise of the sheet, the first row being advantageously spaced from the edge of the sheet a distance of approximately two inches and the spacing between adjacent rows being approximately four inches. Masonry walls are of varying thicknesses, but usually in multiples of four inches, so that by the above described arrangement, locking projections are afforded for each piece of masonry regardless of the angular bends in the material necessary to conform to the joint.

The efficiency of the bond may be increased by forming the projections as ribs, as at 18, Fig. 5, arranged in longitudinal rows, the ribs being inclined to the edge of the material and the ribs of each row being inclined with respect to ribs

of an adjacent row, as shown in Fig. 5. Or if desired, the projections may be in the form of a flanged member or anchor 20 (Fig. 6) adapted to be soldered, riveted or otherwise secured to the material, and of such construction that the masonry may be bonded to the material against movement in all directions.

Within the scope of the invention, the material further may comprise a fabric body 10 connected to each side of a metal sheet 13 (see Fig. 10 2), the outer faces of both sheets being coated with crushed mineral 14 to enable the material to be securely bonded to the mortar on both sides. Or where such bonding is desired on both sides of the material, without materially increasing the thickness of the material, as in Fig. 7, a mortar bonding surface may be provided by securing a crushed mineral surface 21 to the metal coating 13 by means of a layer of asphaltum 22 as in Fig. 8.

As stated above, the improved material is especially adaptable for the waterproofing of masonry joints where angular bending of the material is required. For example, in waterproofing around beams or spandrel joints as shown in Fig. 9, the material may be readily bent to fit over the corner of a concrete floor 23 which may be reinforced with an I-beam 24 or other structural shape. The material is preferably laid in mortar with the stone face surface adjacent the floor 23, and thus a good mortar bond is effected between the mortar and the crushed stone surface. The metal coated surface 13 is above and serves to stop any downward seepage of moisture in the wall and also quickly to drain the moisture from the wall.

After the material is in place, a layer of mortar may be spread upon the metal coated surface 13, and the masonry wall elements 24, and facing stones or brick 25 laid. Upon hardening of the mortar the elements 24 and 25 will be held securely in place and due to the presence of the bonding projections 17, 18 or 20, any tendency of the elements 24 and 25 to shift will be resisted.

In using the invention as a waterproofing around beams or spandrel joints, as in Fig. 9, the relatively thick fabric body 10 is of special utility in providing a pressure relieving joint. The poured concrete floor, for example, will have a different aggregative expansion and contraction than the masonry facing composed of smaller units 24, 25, and the utilization of the resilient, somewhat compressible fabric body provides a pressure-relieving, waterproof joint that will permit of the difference in expansion of adjacent cements without rupture of the mortar joints in the facing.

Advantages of the invention reside in its simplicity, its extreme flexibility, permitting it to be bent readily around joints requiring a plurality of bends. Furthermore, the invention combines with a resilient body, a continuous metal coating for at least one side thereof to provide a water-repelling pressure-relieving waterproof joint material, constructed so as to afford a bond for the superposed or adjacent masonry, to the end that an extremely low priced, highly efficient material is provided which may be installed with a minimum of labor.

It is to be understood that the constructions illustrated in the drawing are intended only as illustrative of the invention, and that the invention may be embodied in various forms and

arrangements without departing from the spirit thereof.

In the claims, the term "fabric" is used to denote broadly a flexible textile paper or like material whether felt sheeting, woven material, such as drilling, or like structures.

I claim:

1. In a masonry building, a supporting masonry structure, masonry facing elements therefor, and a mortar joint between the supporting structure and facing elements, and a waterproof lining for said joint comprising a continuous length of flexible bitumen saturated fabric embedded in and bonded with the mortar of said joint, said lining being flexible and resilient and constituting a pressure-relieving joint means for said joint, said lining having on its upper surface a sheet of copper or the like to prevent penetration of moisture of infiltration into said fabric.
2. A multi-ply flashing material adapted to be embedded in a mortar joint of a masonry structure, one of the plies comprising a flexible bitumen-coated, fibrous sheet material of substantial thickness to form a cushion for a section of a masonry wall, a thin impervious layer of copper uniformly attached to one face of said fabric and serving as a waterproof coating therefor, said metal being sufficiently thin as not to materially impair the flexibility of the fabric whereby said material may be readily bent to conform to a stepped masonry joint, the opposite faces of said multi-ply flashing material being irregular whereby said material may be securely

bonded to a layer of mortar forming a mortar joint of said masonry structure.

3. A multi-ply flashing material adapted to be embedded in a mortar joint of a masonry structure, comprising a flexible sheet of waterproof fibrous material of substantial thickness to form a cushion for a section of a masonry wall, a thin impervious layer of copper uniformly attached to one face of said fabric and serving as a waterproof coating therefor, said metal being sufficiently thin as not to materially impair the flexibility of the fabric whereby said material may be readily bent to conform to a stepped masonry joint, the exposed face of the fibrous material being roughened so as to be securely bonded to a layer of mortar forming a mortar joint of said masonry structure, and means extending upwardly from said material adapted to be embedded in a layer of mortar adhering to the superposed masonry for preventing shifting of said masonry horizontally relative thereto.

4. A masonry structure as defined in claim 1 characterized in that the waterproof lining is a multi-ply structure, one ply comprising a thin, substantially impermeable layer of non-corrodible metal, such as copper, and the other plies comprising waterproofed fibrous material one face of which is facially bonded to the layer of metal and the exposed face of which is roughened, whereby said roughened surface may be securely bonded to the layer of mortar constituting the mortar joint of said structure.
